Primary Examiner — Eric L Goodman*Assistant Examiner* — Vanessa Martinez(74) *Attorney, Agent, or Firm* — Sisson & Banyas, Attorneys at Law, LLC; Jeffrey J. Banyas(57) **CLAIM**

The ornamental design for a vehicle tailgate light as shown and described.

DESCRIPTION

FIG. 1 is a perspective view of a vehicle tailgate light; FIG. 2 is a front view of the vehicle tailgate light; FIG. 3 is a rear view of the vehicle tailgate light; FIG. 4 is a left-side view of the vehicle tailgate light; FIG. 5 is a right-side view of the vehicle tailgate light; FIG. 6 is a top view of the vehicle tailgate light; FIG. 7 is a bottom view of the vehicle tailgate light; and, FIG. 8 is a perspective view of the vehicle tailgate light shown in use.

The broken lines shown in FIGS. 1, 6, and 7 depict portions of the vehicle tailgate light that form no part of the claimed design. The broken lines shown in FIG. 8 depict environmental structure and form no part of the claimed design.

1 Claim, 6 Drawing Sheets(56)
